[57] CLAIM

The ornamental design for a chair for a child's seat or pushcart, as shown and described.

DESCRIPTION

FIG. 1 is an exploded perspective view of a chair for a child's seat or pushcart, showing my new design; the broken lines are for environmental purposes only and form no part of the claimed design;

FIG. 2 is a front exploded elevation according to FIG. 1;

FIG. 3 is a rear exploded elevation according to FIG. 1; FIG. 4 is a left side elevation according to FIG. 1;

FIG. 5 is a bottom view according to FIG. 1;

FIG. 6 is a front perspective view according to FIG. 1, showing the top portion in position;

FIG. 7 is a front perspective view according to FIG. 1, showing the top portion removed;

FIG. 8 is a front perspective view of an alternative embodiment of the chair for a child's seat or pushcart;

FIG. 9 is a top plan view according to FIG. 8, showing the top removed;

FIG. 10 is a front elevation according to FIG. 8, the rear being the same as shown in FIG. 3; and,

FIG. 11 is a left side elevation according to FIG. 8.
